ELECTRIC SWITCH

Fred W. Sonn, Pottstown, Pa.

Application January 10, 1934, Serial No. 706,005

6 Claims. (Cl. 200—6)

This invention relates to electric switches and has for an object to provide a new type of switch adapted to switch the current from one circuit to another and to break the circuit by the continuous movement of a moving part.

A further object of the invention is to provide a switch in circuit with two current consuming devices, and with a movable control member, said switch adapted to function under the control 10 of said movable member to first switch the current from one circuit to the other circuit, and at a further continuance of movement, to break the circuit and to reverse the order upon the reverse movement of the movable part.

15 A further object of the invention is to provide an electric switch especially, though not exclusively, adapted for the control of coils for heating purposes, whereby a coil located in one position is in circuit and the switch is actuated by a moving part to switch the current to a coil 20 in another position, and by a further movement of the part, to break the circuit to both coils and to reverse the order upon reverse movement of the moving part, said moving part being in 25 such heat installation thermostatically controlled.

30 A further object of the invention is to provide an electric switch, especially, though not exclusively, adapted for coaction with a hot water boiler for supplying current to one coil located in heating position relative to the boiler, with thermostatically actuating moving means which, upon movement, will switch the current to a second coil while breaking the circuit to the first mentioned coil, and by a continued movement of such thermostatically controlled part, to break 35 the circuit to both coils, the circuits being made in exactly reverse order upon the reverse movement of the thermostatically controlled moving part.

40 The invention, therefore, comprises a switch device having switch members, one of which is adapted to make the circuit to either one of a plurality of current consuming agencies, another switch being adapted to break the circuit to all 45 current consuming agencies, and a movable part adapted within its limit of movement to perform all of said switching functions, and upon reverse movement, to make the circuits in reverse order.

50 The drawings illustrate an embodiment of the invention, and the several views are as follows:

Figure 1 is a view of the switch in side elevation,

Figure 2 is a top plan view of the switch,

55 Figure 3 is a view of the switch from the side

opposite that shown at Figure 1, and shown in connection with a Bourdon tube as a control,

Figure 4 is a longitudinal sectional view taken on line 4—4 of Figure 2,

Figure 5 is an end view of the switch, as indicated by arrow 5 at Figure 1,

Figure 6 is an end view of the switch as indicated by arrow 6 at Figure 1, and

Figure 7 is a diagrammatic disclosure of one application of the present switch, being applied 10 to a conventional water heater.

Like characters of reference indicate corresponding parts throughout the several views.

The electric switch which forms the subject-matter of this application is adapted for general 15 utility, but is more particularly adapted for thermostatic control of electric heating coils for hot water heaters, and will be so described in the present application, it being understood, however, that the particular combination is only one of 20 many, and that the invention is in no way limited to such combination.

The invention comprises an insulating base block 10 which is mounted in any approved manner. When associated with the installation referred to, the block is preferably mounted upon a bracket 11 which is secured to some type of supporting structure by means of a bolt through the perforation 12. In this type a tube 13 is inserted into the boiler 14 and is, therefore, subjected to the temperature of the water within the boiler. Communicating with this tube 13 is a Bourdon tube 15 and both the tube 13 and the Bourdon tube 15 are filled with some material, liquid preferred, having a high coefficient of expansion, whereby the arcature of the Bourdon tube varies with the temperature of the water in the boiler 14 in the usual, well-known manner.

Under such conditions the block 10 is mounted upon the bracket 11 by means of a bolt 16 passing 40 through a plate 17, which being turned at an angle as at 18, is rigidly secured to the block in any approved manner, as by the bolts or screws 19.

The plate 17 is provided with an elongated slot 20 in which fits a stud 21 mounted eccentrically 45 upon the spindle 22 extending outwardly at the front of the organization. A head 23 is provided for the manual turning of the spindle 22, as indicated more particularly at Figure 1.

A pointer 24 is preferably carried by the spindle 50 22 and movable relative to an arcuate scale 25. The oscillation of the spindle 22 moving the eccentric 21 so that the block 10 may be tilted from full line positions, as shown at Figure 3, to dotted line position indicated at 10' shown in that figure. 55

The reason for this movement will be more apparent as the description progresses.

Mounted upon the block 10 are two uprights 26 and 27 rigidly connected to the block 10 in insulated relation, as by screws 28. These uprights 26 and 27 are, respectively, provided with means diagrammatically represented by the perforations 29 and 30, respectively, for making connection of electrical conductors therewith.

10 Mounted also upon the block 10 is an angle member 31 also provided with means for attaching an electrical conductor therewith, by the perforation 32. This angle member 31 is also rigidly attached to the block 10 and is provided with a contact 33. Mounted also upon the block is a substantially U-shaped member 34 which has a contact 35 overlying the contact 33. This U-shaped member 34 is also provided with a contact 36 on its lower leg, and on its upper leg, with an insulating member 37.

A pair of switch arms 38 and 39 are fulcrumed upon the uprights 26 and 27. This fulcruming is preferably by means of a knife edge connection, as shown at 40 in Figure 4, and in dotted lines at

25 Figures 1 and 2.

These switch arms 38 and 39 are bifurcated, as shown at 41 and 42, respectively, in Figure 2, and perforated at 43 and 44, as seen in the same figure.

30 The loops 45 and 46 of springs 47 and 48 are looped through said perforations 43 and 44, and the opposite ends of said springs are permanently secured to threaded studs 49 and 50, respectively. The position of securing the springs 47 and 48 upon the studs 49 and 50 are adjustable by turning such studs so that the normal pull of said springs from the studs to the loops is independently variable but always below the fulcrums of the arms 38 and 39, tending, therefore, to hold these arms normally yieldingly downwardly.

40 The arm 38 is provided with a double ended contact 51 adapted to make contact with either of the contacts 33 or 35, and held normally in engagement with the contact 33 by the tension of its spring 47.

45 The arm 39 is provided with a single contact 52 which is held normally by the spring 48 in engagement with the contact 36 and is adapted, under the conditions to be hereinafter described, to rise into engagement with the insulating block 50 37, as is also the contact 51 adapted to rise in contact with the contact 35.

50 For actuating the switches a movable finger 53 is located beneath the springs 47 and 48. This finger 53 may be moved in any approved manner, mechanically, or manually, but in the illustrative embodiment, is connected to the Bourdon tube 15 by means of a bracket 54 so that as the Bourdon tube varies its curvature, the finger 53 moves toward or away from the springs 47 and 48 60 and in a further movement, in the direction toward said springs, to lift the springs to the dotted line position as shown at Figure 1. This lifting will throw the tension above the fulcrums 40 of the switch arms 38 and 39 and thereby cause these switch arms to lift from the normal engagement with the contacts 33 and 36, as shown more particularly at Figures 1, 4 and 5, into engagement with the upper contact 35 and the insulating block 37.

70 The relation of the finger 53 and the adjustment of the springs, however, are such that the two switch arms are not actuated simultaneously. As the finger 53 lifts the first result is to lift the spring 47 to a position above the fulcrum of the arm 38 and to thereby break connection between

the contacts 33 and 51 and to make engagement between the contacts 35 and 51.

A continued lifting of the finger 53 performs the same function upon the spring 48, lifting the contact 52 from engagement with the contact 36, the movement being limited by the insulating block 37.

10 It is, therefore, obvious that by tilting the block 10 from the full line position to the dotted line position, as shown at Figure 3, or to intermediate points, the finger 53 is brought relatively nearer to the springs 47 and 48, and is, therefore, in position to actuate said springs sooner, in relation to the movement of the Bourdon tube than when the block is in full line position. The 15 actuation of the switches then takes place upon a minimum variation of temperature, if connected up as shown in the drawings, whereas when in full line positions, the various parts contact only upon a greater variation of temperature. 20

As shown at Figure 7, the boiler 14 is provided with an inner tube 55 in which are located heating coils 56 and 57, conventionally shown. A line wire 58 connects with both of said coils. From the coil 56 a wire 59 leads to the bar 31, 25 which is electrically associated with the contact 36. From the coil 57 a wire 60 leads to the upright 27. The other line wire 61 leads to the upright 26.

30 In operation with both of the switch arms 38 and 39 down, thereby making contact with the contacts 33 and 36, current will flow through the line wire 61 to the upright 26 and through the switch arm 38 to contact 33 and through the bar 31 to the line 59 through the coil 56 to the line wire 58, thereby energizing the coil 56.

35 When the finger 53 has been lifted sufficiently to raise the switch arm 38, so that the contact 51 is in engagement with the contact 35, current will flow through the line wire 61 to the upright 26 through the switch arm 38 and the two contacts mentioned, to the bar 34 to the contact 36, through the contact 52 to the switch arm 39 to the upright 27, line 60 through the coil 57, 40 through the line 58, thereby energizing the coil 45 57.

45 It is apparent that the coil 57 will only take current and be energized after the circuit controlling the coil 56 has been broken and that both of such coils will not be simultaneously 50 energized.

50 When the finger 53 rises a still further distance, as indicated in dotted lines at Figure 1, the switch arm 39 will be raised, thereby breaking the circuit and deenergizing the coil 57. As the finger 53 moves again downwardly, the first switch to close will be the switch arm 38 which will again in the same manner energize the coil 57. Further descent of the finger 53 will break the circuit to the coil 57 and make the circuit to the coil 56.

55 The movement of the finger 53, as has been pointed out, may be accomplished in any approved manner, and the heating coils 56 and 57 are shown merely as illustrating two separate current consuming devices. When employed as a water heating installation, the energizing of the top coil 56 will, of course, heat the water in the top of the boiler. When this has been heated to such an extent that the inserted tube 18 has responded to the heat and thereby expanded the Bourdon tube, the finger will be raised to break the circuit to the coil 56 and make the circuit to the coil 57. This will supply heat to the bottom of the boiler. 70 75

If now the entire contents were raised to such a temperature that the Bourdon tube is further expanded, then the finger 53 will raise the spring 48 and the switch arm 38 and break the circuit 5 so that all energizing ceases.

It is obvious that connected to any other two current consuming devices, the action of energizing the two would be the same and the result would be the same whether the finger 53 is operated automatically by the position of the Bourdon tube or manually, mechanically, or otherwise.

It will be obvious that the present invention comprehends a switch including only a single switch arm, as for instance, the arm 38. It is also obvious that it may include a greater number of switch arms than the two shown and described. The invention is, therefore, to be understood as directed toward the construction and operation of one or more switch arms with its or their associated spring or springs, and with a movable finger operating directly upon the spring or springs for actuating the switch arm or arms.

Of course, the electric switch herein illustrated may be modified and changed in various ways without departing from the invention herein set forth and hereinafter claimed.

I claim:—

30 1. A switch comprising a base block, an upright intermediate the ends thereof, cooperating switch arms having corresponding ends fulcrumed in the upright and extending toward one end of the base, switch contacts cooperating with said extended ends, posts erected on the base adjacent to the end opposite the contacts, springs attached to the posts and spanning the fulcrum attached to the switch arms tensioned to hold the switch arms at one limit of movement, and means 35 moving laterally, in the same direction relative to both springs to successively shift the tension across the fulcrums to move the switch arms to the opposite limit of movement.

2. A switch comprising a base block, an upright intermediate the ends thereof, cooperating switch arms having corresponding ends fulcrumed in the upright and extending toward one end of the base, switch contacts cooperating with said extended ends, threaded posts erected on the base adjacent to the end opposite the contacts, springs attached to the posts by loops engaging the

threads and spanning the fulcrum attached to the switch arms tensioned to hold the switch arms at one limit of movement, and means moving laterally, in the same direction relative to the springs to successively shift the tensions across the fulcrums to move the switch arms to the opposite limit of movement.

5

3. A switch organization comprising a Bourdon tube, a base block pivoted relative to the Bourdon tube, a switch arm fulcrumed upon the base block, 10 a spring positioned to exert tension across the fulcrum, a finger carried by the Bourdon tube positioned to exert pressure upon the spring laterally tending to shift the tension across the fulcrum, and means to tilt the base upon its pivot 15 to bring the fingers into action at different positions of the tube.

4. A switch organization comprising a Bourdon tube, a base block pivoted relative to the Bourdon tube, a switch arm fulcrumed upon the base block, 20 a spring positioned to exert tension across and normally upon one side of the fulcrum, a finger carried by the Bourdon tube positioned to exert pressure upon the spring laterally tending to shift the tension across to the opposite side of 25 the fulcrum, and means to tilt the base upon its pivot to bring the finger into action at different positions of the tube.

5. A switch organization comprising a Bourdon tube, a base block pivoted relative to the Bourdon tube, a plurality of cooperating switch arms fulcrumed upon the base, springs positioned to exert tension across the fulcrum, a finger carried by the Bourdon tube positioned to exert pressure upon the springs tending to shift the tensions 30 across the fulcrums, and means to tilt the base upon its pivot to bring the finger into action at different positions of the tube.

30

35 6. A switch organization comprising a Bourdon tube, a base block pivoted relative to the Bourdon tube, a plurality of cooperating switch arms fulcrumed upon the base, springs positioned to exert tension across and normally upon one side of the fulcrum, a finger carried by the Bourdon tube positioned to exert pressure laterally and 40 successively upon the springs tending to shift the tensions successively across to the opposite sides of the fulcrums, and means to tilt the base upon its pivot to bring the finger into action at different positions of the tube.
